UNITED STATES PATENT OFFICE.

GEORGE STANLEY PETERS, OF SULLIVAN, ILLINOIS.

ELECTRICAL ADVERTISING DEVICE.

1,293,187.

Specification of Letters Patent.

Patented Feb. 4, 1919.

Application filed March 6, 1917. Serial No. 152,594.

To all whom it may concern:

Be it known that I, GEORGE STANLEY PETERS, a citizen of the United States, residing at Sullivan, in county of Moultrie and State of Illinois, have invented certain new and useful Improvements in Electrical Advertising Devices, of which the following is a specification.

My invention relates to an improvement in electrical advertising devices, and pertains more particularly to an improvement in show-case illuminators and goods displayers.

The object of my invention is to provide means whereby a container in a show-case has a lamp directly attached thereto, and which is arranged to light and be extinguished as desired.

A further object of the invention is to provide such a support as will permit the ready withdrawal of a container therefrom, and which has on its face two electrodes or connecting points for making a circuit on the lamp through the container.

A still further object is to provide an attachment for containers, which is so made that a lamp may be firmly fastened to a container, and be illuminated at certain intervals, and so made that the container may be freely handled without affecting the lamp or its support.

In the accompanying drawings forming part of this specification:—

Figure 1 is a view of a show-case with my invention in place;

Fig. 2 is a perspective view of the base upon which the container rests;

Fig. 3 is a detached perspective view of the part of the invention applied to the container proper; and

Fig. 4 shows the container in position to be operated.

The base 1 has located therein two contact points 2 and 3, which are connected with the wire 4 running to a switch (not shown).

The base 1 has rigid brackets 5, and brackets 6, 6, at the sides thereof, and a vertically adjustable support 7 at the rear of the base to regulate the height of the back of the container.

The combined lid-holder and electrical connection comprises a longitudinal strip 8 preferably made of a non-conductor, such as wood having exposed contacts 9 and 10 connected in turn with the wire 11, which

connects with the opposite poles of the lamp-socket 12.

The longitudinal strip 8 is provided at one end with a coiled spring 13, terminating in a clip 14. The other end of the longitudinal strip 8 terminates in a substantially right-angled strip of metal 15, pivotally fastened to the flanged strip 16 and frictionally held by a bolt 17 and nut 18. The strip 16 is also provided with the clips 19 and 20 adapted to engage the upper and lower edges of the container. At one end of the strip 16, a bar 21 extends at right-angles, flanged at its upper edge to form the support 22.

The operation of the device is as follows:—The longitudinal strip 8 is secured to the bottom of the container, such as a cigar-box, and is held by the spring 13 and clip 14 at one end, and by the strip 16, and clips 19 and 20 at the other. The portions 21 and 22 are adapted to extend behind the box, and to support the lid in various positions, according to the angle of the bar 21. A lamp is screwed into the socket 12, and the box is placed upon the base 1, where lateral movement is prevented by the brackets 5 and 6.

When the box is in position on the base, the contacts 2 and 3 will be engaged by the contacts 9 and 10, and the switch at the end of the wire 4 (not shown) will close the circuit through wire 4, the contacts 2 and 3, through the lamp. This may be done by as many switches as there are doors, and as soon as the box which the customer has designated is raised from the base 1, the circuit will be broken, and the lamp will go out, and the cigar-box or other container may be offered to the customer as in the ordinary show-case.

It is obvious that many slight changes of structure may be made, hence I do not wish to be limited to the precise construction shown, but:—

I claim:

1. In a display device, the combination with a base, of an electrical circuit adapted to be closed at certain times and to pass through the base, a container, detachable means on said container carrying an illuminant, and conductors extending from the illuminant to points on said detachable means, said means adapted to rest upon the base and to complete the circuit, the whole

so arranged that placing the container upon the base completes the circuit through the illuminant.

2. An advertising device comprising a supporting structure, means for detachably securing the supporting structure to a box, an upwardly inclined extension upon the supporting structure adapted for supporting the lid of the box in an open position, a vertical extension formed on the supporting structure, an electric lamp socket carried by said extension and adapted to be disposed over the box, an electric lamp carried by said socket, and means for illuminating the electric lamp.

3. An advertising device comprising an arm, means for securing the arm to one of the walls of a box, an electric lamp carried by said arm, a vertical arm secured to said arm, a bar secured to the vertical arm and

adapted to underlie the box, means for detachably securing the bar to the box, and means for illuminating the electric lamp.

4. An advertising device comprising an arm, means for detachably securing the arm to one wall of a box, a vertical arm secured to said arm, a bar extending from the vertical arm and adapted to underlie the box, a spring secured to the bar adapted to be secured to one wall of the box, an electric lamp carried by the first-mentioned arm, contacts carried by the bar, a base, supports carried by said base, and some of said supports engaging the contacts, and means for electrically connecting some of the supports to an electrical source for illuminating the electric lamp.

In testimony whereof I affix my signature.

GEORGE STANLEY PETERS.
